CARTON STAMPING MEANS

Edgar L. Stevens, 3035 10th Parkway, Vero Beach, Fla.
Filed Aug. 28, 1963, Ser. No. 305,128
6 Claims. (Cl. 101—42)

This invention relates to printing or stamping devices and more particularly to a device especially adapted for stamping or marking cartons or other containers such as cartons of the type generally used for containing fruit, vegetables or many other products.

It is an object of the invention to provide a device of this type which can be mounted on or located adjacent to a supporting table or other surface upon which a carton is rested and which presents a vertical wall for imprinting and which will be imprinted by the simple manual swing of an operating handle forming a part of the printing device.

It is an object of the invention to provide a printing device of this character which will be of a relatively simple and sturdy construction, and one by which a plurality of separably useable stamps or imprinters can be used together or selectively; which will be self-inking in that it is provided with suitable inking means, and which can if desired, be provided with counting means for indicating the number of cartons stamped.

More particularly, the invention contemplates the use of a pivotal or hinged carrier for a plurality of stamps or imprinters and which carrier is swingable to and from the vertical wall surface of the carton to be imprinted. The invention further contemplates the provision of movable inking means for the imprinters and of means for moving the inking means out of the path of travel of the imprinters as they are moved to imprinting position, and also of means to return said inking means to position in front of the imprinters as the same are moved back to their retracted or rest positions away from the carton.

With these and other objects to be hereinafter set forth in view, I have devised the arrangement of parts to be described and more particularly pointed out in the claims appended hereto.

In the accompanying drawings, wherein an illustrative embodiment of the invention is disclosed,

FIG. 1 is a side elevational view of a stamping device or imprinter constructed according to the invention and with some of its parts shown in section;

FIG. 2 is a top plan view of the same;

FIG. 3 is an elevational view of the device as seen from the opposite side of FIG. 1, and with the parts shown in their inoperative or rest position;

FIG. 4 is a sectional view, taken substantially on the line 4—4 of FIG. 3, looking in the direction of the arrows;

FIG. 5 is a rear view of the device as seen from the right of FIG. 3;

FIG. 6 is a view similar to FIG. 3, but showing the device in the act of imprinting;

FIG. 7 is a sectional view, taken substantially on the line 7—7 of FIG. 6, looking in the direction of the arrows;

FIG. 8 is a sectional view, taken substantially on the line 8—8 of FIG. 3, looking in the direction of the arrows, and

FIG. 9 is a sectional view, taken substantially on the line 9—9 of FIG. 3, looking in the direction of the arrows.

The improved stamping or imprinting device is one particularly adapted for stamping or marking printed matter upon the side wall or end of a carton or other container such as, for example, one for containing fruit, vegetables and many other articles. Such a carton, in

2

position for the application of the printing, is shown at 1 and it rests upon a supporting table or shelf 7 on which it may have been placed by conveying means or manually positioned thereon. The table is supported from the floor by legs 6 or suitable framework. The mechanism

5 for performing the printing or stamping operation can be fixed to the supporting table to locate it adjacent to the carton, and it is arranged in such a position that the carton 1 will present a side or wall portion 1a in a position to receive the imprint from the stamping apparatus.

10 The stamping or printing device, in the embodiment disclosed, includes an upper impression holder, stamp or imprinter 9 bearing suitable changeable lettering, numerals or other indicia, such as that indicating the operator or packer's number, as shown at 20. At 10 is shown

15 a central impression holder or stamp which might have the changeable lettering 21 to indicate the type of fruit, vegetable, etc. contained within the carton. At 11 is shown a third or lower impression holder or printer which can indicate, for example, the quantity of fruit or other goods contained within the carton. Each of the impression holders or imprinters 9 and 10 is secured on rods 22

20 slidably mounted through a hollow support or casing 23, and coil springs 24 (FIG. 8) are interposed between the back of each of the impression holders and a washer 25

25 disposed against the forward wall 26 of the casing 23. This arrangement is such that a springy or resilient mounting is provided for each of the imprinters 9 and 10 and as later explained herein, a means by which the imprinters can be moved to an inoperative or retracted position when desired.

The third impression holder or stamp 11, shown in detail in FIG. 9, consists of a roller or drum 35 rotative on an axle 36 mounted between plates 37, connected at one end by a U-shaped yoke 38. One of the plates 37 is fastened to a bar or lever arm 15, to be described, so that a swinging movement of this bar toward the carton surface 1a will bring the impression members or imprinters 9, 10 and 11 in contact with the carton surface to thereby produce the desired imprinting on the same.

40 The indicia borne by the impression members or imprinters is preferably changeable and that borne by the impression member or stamp 11 is very quickly alterable since such indicia has its characters mounted on a flexible belt 39 which passes around the roller or drum 35 and extends over the U-shaped member or yoke 38 which serves as a backing for the belt 39, particularly during the printing operation.

The casing 23, in which the imprinters 9 and 10 are mounted is fixed to the bar 15 by screws 70 or equivalent fasteners, and said bar 15 constitutes an arm of a bell-crank lever which is pivoted at 17 to a bracket 8 mounted on the part 6 of the frame of the table 7. The second arm of the bell crank, shown at 30, extends through an aperture 24 in the support 6 and is biased upwardly by means of a coil spring 18 surrounding a rod 25 bearing against the underside of the table top 7. The lower end of this rod 25 is provided with a head or disk 26 forming a spring seat for the coil spring 18, the upper end of the spring 18 bearing against an angular bracket 29 engaging 55 with and secured to the arm 30 as clearly seen in FIGS. 3, 5 and 6.

Inking pads for the stamps or impression members 9, 10 and 11 are shown respectively at 32 and 33 and 34, and the upper and lower inking pads 32 and 33 are carried 60 on a radial extension of a sleeve 40 which is rotatable around a rod or post 41. The rod 41 extends through a slot 42 in a bracket 43 which extends transversely across and is attached to a pair of parallel bars, one of which is the arm or lever 15 and the other bar is that shown at 44 which is pivoted at one end as shown at 45, to the bracket 70 43. The last-mentioned bar, or that shown at 44, is joined

in parallel relation to the bar or lever 15 by means of the bracket 43, and at the end opposite to its pivot 45 by a cross-piece 46. An operating handle 47 is provided at the upper end of the bar or lever 15.

At its lower end, the sleeve 40 has an angular extension or plate 48 which carries the inking pad 34 for the lower impression member or stamping device 11. The device is so operative that when the stamps or imprinters 9, 10 and 11 are swung from their retracted position, or position of rest as shown in FIG. 3, and wherein they are in contact with the respective inking pads 32, 33 and 34, these inking pads will be swung out of the path of travel of the imprinters 9, 10 and 11 so that the imprinters may be moved into contact with the wall 1a of the carton to apply the markings thereon.

To secure the required movement of the inking pads out of the way of the stamps or imprinters 9, 10 and 11, the sleeve 40 carrying the several inking pads, is rotatively movable on a vertical axis around the rod or post 41 which is anchored at one end in the bracket 8. The sleeve 40 is provided at its upper end with a radially projecting lug 50, normally disposed in the path of swing of the cross member 46 by means of a torsional spring 51 surrounding the rod 41 at the lower end of the sleeve 40.

By means of the spring 51, the sleeve 40 is normally positioned so that the inking pads carried by it are disposed in front of the impression members or imprinters 9, 10 and 11. When the operating handle 47 is engaged and the lever 15 is swung toward the left as viewed in FIG. 3, or in the direction of the arrows 52, the cross piece 46 will contact with the lug 50 and rotate the sleeve 40 in opposition to the torsion of spring 51 and thus swing the several inking pads out of the path of movement of the several stamps or imprinters 9, 10 and 11, allowing the same to contact with the carton and apply the imprint thereon. When the bar 15, which is the carrier for the imprinters, swings backwardly or toward the right as viewed in FIG. 3, and which return movement is effected by the action of the spring 18 acting on the arm 30, the rotative return movement of the sleeve 40 will be halted by the contact of the lug 50 with a stop member 53 provided on the head 54 of the rod or post 41, thus positioning the inking pads in front of the imprinters or stamps.

Means is provided by which either of the stamps or imprinters can be held out of printing position. For this purpose, there is provided on each of the rods 22, an L-shaped plate 55, located between a head 56 on the rod 22, and a washer 57 bearing against the rear wall of the casing 23. When the foot portion 58 of the plate 55 extends beyond the casing as shown in FIG. 8, the stamp or imprinter will be located in the required position for imprinting when the handle 47 is swung in a direction toward the carton. By turning the L-shaped plates 55 to the dotted line positions of FIG. 5, to bring the feet 58 thereof against the back wall of the casing 23, the stamps or imprinters 9 and 10 will be retracted or drawn back and held from contact with the carton. The stamp or imprinter shown at 11 can be moved to an inoperative position by swinging it bodily around the pivot 36.

Connected to the bars 15 and 44 is a counter 60 having an operating button 61. The button 61 is actuated by spring finger 62 that is connected to the bracket 43 and whereby the counter is actuated at each stamping movement of the device. The use of this counter may be eliminated, if desired.

From the foregoing, the operation of the improved stamping or marking device will be apparent. A carton to be stamped is rested upon the table or other support 7, and to which the carton may be brought by conveying or other means, and with the end or side of the carton to be imprinted presented toward the stamping device. The inoperative or rest position of the device is shown in FIG. 3 wherein it will be noted that the stamps or imprinters are located away from the carton and are in contact with the inking pads 32, 33 and 34. The operator

grasps the handle 47 and swings the bar or lever 15 in the direction of the arrows 52, and as this is done, the cross piece 46 will contact the lug 50 and rotate the sleeve 40 around its vertical axis, thereby bringing the inking pads 32, 33 and 34 out of the path of travel of the stamps or imprinters 9, 10 and 11, which are then free to come into contact with the wall 1a of the carton and apply the printing thereon. The apparatus at this time is as shown in FIG. 6, and with the spring 18 compressed. Upon the release of manual force on the handle 47, the spring 18 will tend to restore the bell-crank lever, of which the bar 15 is a part, to its former position by swinging it toward the right, and as the bar nears its position of complete retraction it will permit the inking pads to be moved back into their operative positions in front of and into contact with the surfaces of the imprinters, under the torsion of spring 51, acting on the sleeve 40.

The device is simple and effective in operation. It requires merely a swing of the operating lever 15 for each impression, so that it can be operated as fast as the cartons are presented to it from a conveyor or else are manually placed in position for marking.

Having thus described a single embodiment of the invention, it is obvious that the same is not to be restricted thereto, but is broad enough to cover all structures coming within the scope of the annexed claims.

What I claim is:

1. A marking device for cartons comprising a carton support on which a carton rests and presents a vertical wall for printing upon it, a manually-operated lever pivoted at one end to the support, a plurality of spaced imprinters carried by the lever and caused to be brought against said wall of the carton upon swing of the lever in one direction, a fixed vertical post, a sleeve extending around said post and rotatively movable on the same, spaced inking pads carried by the sleeve, a torsion spring operative on the sleeve to bias the same in a manner to position its inking pads against the imprinters when the imprinters are positioned away from the wall of the carton, a radial projection on one end of the sleeve, a projection on the lever and situated to impinge against the projection on the sleeve to thereby rotatively move the sleeve around the post and cause the inking pads to be moved in opposition to the force of the spring out of the path of travel of the imprinters as the imprinters are moved in a direction toward the carton by a swinging movement of the lever.

2. A marking device as provided for in claim 1, wherein stop means is provided to limit the swing of the sleeve under the force of the torsional spring and thereby locate the inking pads in front of the imprinters, means for resiliently mounting the imprinters on the lever, means for selectively retracting the imprinters from printing positions, and one of the imprinters having marking indicia borne by a belt, and a support over which the belt is adjustable.

3. A marking device for cartons comprising, a support on which a carton is rested to present a vertical wall for imprinting, a bracket on the support, said bell-crank lever having one arm constituting a hand lever and carrying a stamp holder, a plurality of stamps resiliently mounted on the holder, an additional stamp mounted on the lever below the holder, the latter stamp including an adjustable belt bearing marking indicia, a fixed vertical post having its lower end mounted on the bracket, a sleeve rotative on the post, inking pads carried by the sleeve, spring means encircling the post and engaging the sleeve and tending to hold it so that its inking pads are disposed in front of all of the stamps, and interacting means on the sleeve and on the lever for rotatively moving the sleeve to cause the inking pads thereon to be moved from in front of the stamps when the stamp-carrying lever is swung in a direction toward the carton surface to be imprinted, the bell crank having a second arm, and spring means for biasing

said last-mentioned arm to urge the stamp-carrying arm in a direction away from the carton.

4. A marking device for cartons comprising, supporting means for a carton, a pivoted bell-crank lever mounted on a horizontal pivot and having a first arm constituting a hand lever, resiliently mounted imprinters carried by said arm, the bell-crank lever having a second arm, spring means for biasing said second arm in a manner to cause the first arm to have its imprinters normally disposed away from the carton, a pivoted bar extending substantially parallel to the first arm of the bell-crank lever and connected thereto, a fixedly-mounted vertical post, a sleeve fitted around the post and rotative thereon, at least one inking pad carried from the post, spring means for normally interposing the pad in the path of swing of the first arm of the bell-crank lever, a lug projecting from the sleeve, and a member carried by the bar for contacting said lug as the imprinters are moved toward the carton, whereby said member will rotate the sleeve around the vertical post in opposition to the bias of its spring means and thus move the inking pad out of the path of the imprinters as they are moved to imprinting position.

5. A marking device according to claim 4, wherein the first arm of the bell-crank lever and the bar are attached to a housing, the imprinters having stems slidable through

10

the housing and being spring-biased in a direction away from the housing to an advanced imprinting position, and means mounted around each of the stems by which any one of the imprinters can be retracted to a non-printing position in opposition to the bias of its spring.

6. A marking device as provided for in claim 5, wherein the means for retracting any one of the imprinters consists of a plate rotative around the stem of the imprinter, said plate having an offset end for disposition against the housing to thereby retract the imprinter.
